PLASTIC FIGURED TEXTILE FABRIC

Richard C. McEwan, Lloyd's Harbor, N.Y., assignor to Riegel Textile Corporation, a corporation of Delaware

Filed Sept. 29, 1960, Ser. No. 62,302

Term of patent 14 years

(Cl. D87—3)

Fig. 2

Fig. 3

FIG. 1 is a plan view of a plastic figured textile fabric embodying the design of the present invention with the repeating pattern of the present design outlined in dotted lines.

FIG. 2 is an enlarged plan view of a portion of the fabric of FIG. 1.

FIG. 3 is a sectional view taken on the line 3—3 of FIG. 2.

I claim:

The ornamental design for a plastic figured textile fabric, as shown and described.
